CAR SEAT FOR A CHILD

Stephen J. Molitoris, Ann Arbor, Mich., assignor to
American Safety Equipment Corporation, Sher-
man Oaks, Calif., a corporation of New York

Filed Sept. 24, 1968, Ser. No. 13,693

Term of patent 14 years

Int. Cl. D6—01

U.S. Cl. D15—1

FIG. 1.

FIG. 7.

FIG. 2.

FIG. 8.

FIG. 3.

FIG. 3.

FIG. 6.

FIG. 4.

FIG. 6.

FIG. 1 is a perspective view showing my new design for a car seat for a child;

FIG. 2 is a side elevation view of the article shown in FIG. 1;

FIG. 3 is a front elevation view of the article shown in FIG. 1;

FIG. 4 is a rear elevation view of the article shown in FIG. 1;

FIG. 5 is a sectional view of the article shown in FIG. 3 taken along the plane V—V;

FIG. 6 is a sectional view of the article shown in FIG. 5 taken along the plane VI—VI;

FIG. 7 is a sectional view of the article shown in FIG. 5 taken along the plane VII—VII; and

FIG. 8 is a sectional view of the article shown in FIG. 7 taken along the plane VIII—VIII.

The side of the car seat not shown is a mirror image of the side shown.

I claim:

The ornamental design for a car seat for a child, as shown and described.
